UNITED STATES PATENT OFFICE

ROBERT E. SCHRODER, OF CHICAGO, ILLINOIS, ASSIGNOR TO GOODMAN MANUFACTURING COMPANY, OF CHICAGO, ILLINOIS, A CORPORATION OF ILLINOIS

LOADING MACHINE

Application filed March 12, 1930. Serial No. 435,064.

This invention relates to improvements in loading machines of the type adapted to be moved into the material to be loaded and about the mine on track wheels on the mine 5 rails or on traction thread devices, and has among other objects to provide a loading machine which may readily gather and load loose material such as coal in relatively low narrow working places which is provided 10 with a new and improved form of gathering mechanism having a loading action similar to that of the ordinary hand shovel for increasing the efficiency of loading and gathering with a minimum breakage of material 15 gathered.

In carrying out my invention I provide a new and improved form of gathering mechanism including a plurality of scoops adapted 20 to have a forward horizontal scraping or digging movement and a rearward angular conveying movement so as to engage and carry the loose material onto a conveyor with improved means for continuously operating said scoops in a manner similar to that of 25 an ordinary hand shovel.

Other objects of my invention will appear from time to time as this specification proceeds.

My invention may be more readily understood with reference to the accompanying drawings wherein:

Figure 1 is a top plan view of the device embodying my invention;

Figure 2 is a side elevation of the device 35 shown in Figure 1;

Figure 3 is an enlarged partial fragmentary plan view of the device shown in Figure 1 with parts broken away and in section to more clearly show the details of my invention;

Figure 4 is a partial fragmentary sectional view taken on line 4-4 of Figure 1;

Figure 5 is an enlarged partial fragmentary side elevation of the device shown in 45 Figure 1 with parts broken away and in section to more clearly show the details of my invention;

Figure 6 is an enlarged partial fragmentary side elevation of the device shown in 50 Figure 1 with different parts broken away

and in section than in Figure 5 to show other details of my invention;

Figure 7 is an enlarged view of the front portion of my machine with parts broken away and in section to more clearly show the 55 details of the gathering mechanism;

Figure 8 is an enlarged partial fragmentary view of the front portion of the machine to more clearly show the details of the gathering 60 mechanism; and

Figure 9 is an enlarged partial fragmentary view of the rearward portion of the drive means for the gathering mechanism to more clearly show the details of the gathering 65 mechanism.

Like numerals refer to like parts throughout the various figures.

Referring now in particular to the drawings, the device embodying my invention includes a base frame 1 having a gathering element 2 projecting forwardly therefrom and a storage and conveying element 3 mounted thereon rearwardly of the gathering element 2 for pivotal movement with respect thereto. The base frame 1 is supported on a plurality 70 of laterally spaced continuous tread devices 4-4 for movement about a mine.

A motor 5 is supported on the rearward portion of the base frame 1 and has driving connection with the continuous tread devices 80 4 through a suitable geared reduction; as, for instance; an armature pinion 7 on a motor shaft 8 which drives spur gears 9-9 on longitudinal shafts 10-10 spaced on each side of said motor shaft and parallel thereto. A

worm 11 is freely mounted on each shaft 10 and is driven thereby through suitable clutch means generally indicated at 12, said clutch means being herein shown as a friction cone 85 clutch of an ordinary construction. The worms 11 mesh with and drive worm gears 14 on a transverse shaft 15. The worm gears 14 each have driving connection with a continuous tread device 4 through a usual drive 90 sprocket in an ordinary manner not herein shown. Thus the continuous tread devices 4 may be independently controlled to facilitate turning of the machine; as, for instance; by applying power to one continuous tread de- 100

vice and releasing power from the opposite continuous tread device.

The storage and conveying element 3 comprises a conveyor frame 17 pivoted at its forward end on a base plate 18 to move about the axis of a transverse shaft 16. The base plate 18 is mounted on the base frame 1 for rotatable movement thereabout. Balls 19 are interposed between the base plate 18 and a circular supporting member 20 of the base frame 1. A shoulder 21 depending from the base plate 18 abuts the outer periphery of the circular supporting member 20 for guiding said plate as it is rotated about said circular supporting member.

A shaft 23 is fixed to the base plate 18 and depends therefrom and is journaled in a boss 24 integral with the supporting member 20. A worm gear 25 is fixed to the lower end of said shaft and is driven by a worm 26 on a shaft 27. A suitable gearing arrangement is provided for driving the worm 26 in opposite directions from the motor 5 without reversing said motor which herein comprises a pinion 28 on the forward end of the motor shaft 8, which motor shaft extends forwardly beyond the armature pinion 7. The pinion 28 meshes with and drives a gear 29 on a shaft 30. The shaft 30 is journaled in the base frame 1 and has spur gears 31 and 32 freely mounted thereon. The spur gear 31 meshes with an idler gear 33, which idler gear meshes with a spur gear 34 keyed on the shaft 27. The spur gear 32 meshes with a spur gear 35 keyed on the shaft 27 for driving said shaft in an opposite direction than the gear 34. Suitable clutch means, herein shown as jaw clutch means generally indicated at 36, are provided to operatively connect either the gear 31 or 32 to the shaft 30 for rotating the base plate 18 and storage and conveying element 3 about the axis of the shaft 23 without reversing the motor 5.

Suitable conveying means are carried on the conveyor frame 17, which means herein comprise a belt conveyor 37 having a plurality of flights 38 attached thereto. The belt conveyor 37 is driven from a motor 39 attached to the conveyor frame 17 through an armature shaft 40, worm 41, worm gear 42, and chain and sprocket drive generally indicated at 43.

The motor 39 besides driving the conveyor 37 also provides a means for vertically moving the conveyor frame 17 about the axis of the shaft 16. A worm 45 is freely mounted on the rearward end of the armature shaft 40 and may be selectively connected therewith by means of suitable clutch means herein shown as a pin clutch 46 of an ordinary construction. A worm gear 47 on a transverse shaft 48 meshes with and is driven by the worm 45. The transverse shaft 48 is journaled in the base plate 18 and extends transversely of said base plate on

each side of the conveyor frame 17. Sprockets 50 are fixed on said shaft adjacent opposite sides of the conveyor frame 17. A bracket 51 integral with the motor housing and housing for the worm 45 and worm gear 47 extends upwardly from the base plate 18. A corresponding bracket 52 extends upwardly from the base plate 18 on the opposite side of the conveyor frame 17. Sprockets 55 are journaled in the top portion of the brackets 51 and 52. Suitable drive chains 56 are trained around the sprockets 50 and 55 and are driven from the transverse shaft 48. Each drive chain 56 has connection with the conveyor frame 17 at opposite sides of said conveyor frame, said connection herein comprising a link 57 pivotally connected to a depending portion 58 of said frame. Thus movement of the chains 56 in one direction or the other raises or lowers the conveyor frame 17 to accommodate said conveyor frame to various heights of mine cars and varying roof conditions. The worm 45 and worm gear 47 are of the self locking type so the conveyor frame 17 may be locked in its various desired positions with respect to the base plate 18.

Means are provided for guiding the material gathered by the gathering element 2, which means also serves as a means for storing the loose material when the gathering element is operative and the conveying element is inoperative; as, for instance, when it is desired to gather material and there are no cars available in which to gather said material. Said means herein comprises a hopper generally indicated at 59.

The hopper 59 is slidably mounted on the conveyor frame 17 to compensate for vertical and horizontal movement of said conveyor frame with respect to the gathering element 2, and includes a deflecting pan 60 adjacent the rearward end of the gathering element 2 having sides 61 thereon adjacent the inner portion of side frame members 62 of the gathering element 2. Inwardly extending side members 63 are pivotally connected to the sides 61 of the deflecting pan 60. These side members are in turn connected to hinged supports 64 which are connected to the forward end of side pieces 67 slidable in longitudinal guides 65 adjacent each side of the conveyor 37. The side pieces 67 are each provided with a T-shaped foot 66, which foot is slidable in the guides 65 as is shown in detail in Figure 4. The pieces 67 extend rearwardly from the hinged supports 64 and are engageable with longitudinal slots 68 on each side of the conveyor frame 17 for longitudinal movement with respect thereto. It may thus be seen that the deflecting pan 60 is supported on the side pieces 67 and that these side pieces are independently slidable longitudinally of the conveyor 37 to compensate for both vertical

and horizontal movement of the conveyor frame 17 and belt conveyor 37 during the loading operation.

Referring now in particular to the gathering element 2 forming one of the principal features of my invention, a continuous material gathering device has been provided of a novel construction which is moved under the loose material along the mine bottom in a substantially horizontal plane with an action similar to that of the ordinary hand shovel and which raises said loose material and conveys it rearwardly into the hopper 59 and conveyor 37, which conveyor loads the material into a mine car or other suitable receptacle.

The gathering element 2 includes the side frame members 62, which members are connected together by means of a transversely extending girder 71 and a transverse plate 69 near their lower forward ends. The top portion of the transverse plate 69 forms a guide for the gathering means while the bottom portion of said transverse plate is adapted to act as a shoe to engage the mine bottom and slide therealong as the machine is moved into the loose material by the continuous treads 4. (See Figure 7.)

The side frame members 62 are mounted on sleeves 70 extending outwardly from opposite sides of the base frame 1. The sleeves 70 are fixed in the base frame 1 and their outer surface which projects beyond said base frame serves as a bearing support for the side frame members 62. Lever arms 72 extend rearwardly from the side frame members 62 and are integral therewith. Crank arms 73 are keyed on opposite ends of a transverse shaft 74. The forward end of each crank arm 73 is forked and has a block 75 supported between the prongs of the forked portion by means of a pin 76. The block 75 engages a guide 77 in the rearward end of the lever arm 72 so that movement of the crank arms 73 about the axis of the shaft 74 pivots the lever arms 72 about the axis of the sleeves 70 which in turn raises or lowers the forward portion of the gathering element 2.

A lever arm 79 is keyed on the shaft 74 intermediate the ends thereof and is so arranged that it may be engaged by a threaded shaft 80 threaded within a worm gear 81. It may be here noted that a space is left between the lower portion of the shaft 80 and lever 79 to allow a certain amount of free movement of the gathering element 2 about the sleeves 70. The worm gear 81 is supported in bearings 82 and 83 attached to the base frame 1. A sleeve 84 is journaled within the worm gear 81 and is feathered to the threaded shaft 80. A brake drum 85 is integral with the top portion of the sleeve 84 and may be engaged by a friction band 86, which friction band is engaged with or disengaged from the brake drum 85 by means of a suitable system of levers in an ordinary manner. Rotation of the worm gear 81 rotates the threaded shaft 80 and sleeve 84. When the sleeve 84 is held from rotation by the friction band 86, the threaded shaft 80 is moved vertically through said sleeve to engage or disengage the lever arm 79 depending upon the direction of rotation of the worm gear 81 and move the end of said lever arm downwardly or allow said end to raise to move the transverse shaft 74 about its pivotal axis. Thus pivotal movement of the transverse shaft 74 causes movement of the crank arms 73 which raises or lowers the forward end of the gathering element 2. The worm gear 81 is driven by the motor 5 through a worm 87 on the longitudinal shaft 30.

It may thus be seen that a simple means has been provided for raising or lowering the forward portion of the gathering element 2 to compensate for a rough or uneven mine bottom and to allow the loading machine to be readily moved about the mine from one working place to another.

Referring now in particular to the details of the continuous gathering mechanism, details of which are shown in Figures 3, 5, 7, 8 and 9, a pair of parallel spaced drive chains 88 are provided for driving the continuous gathering mechanism. These drive chains are on opposite sides of the gathering element 2 near the outer ends thereof, and are driven from the motor 5 through sprockets 89 and drive shaft 90. The drive shaft 90 is journaled within the sleeves 70 and the base frame 1, and is driven from the motor 5 through a longitudinal shaft 93 and a worm and worm gear drive generally indicated at 92. The longitudinal shaft 93 is driven from the motor shaft 8 through the pinion 28 and spur gear 94 fixed on a clutch member 95 freely mounted on the shaft 93. The forward face of the clutch member 95 is provided with depressions to receive balls 96. A sleeve 97 is freely mounted on the shaft 93 and has a rearward face 98 adjacent the forward face of the clutch member 95, which rearward face has depressions therein for receiving the balls 96. Suitable compression means are provided to engage the depressions in the face 98 of the sleeve 97 with the balls 96, which means as herein shown includes a member 99 surrounding the sleeve 97 and abutting a shoulder 100 on said sleeve. The member 99 is held in engagement with the sleeve 97 by means of cap screws 101 and compression springs 102. The cap screws 101 are threaded in a flange 103 integral with the clutch member 95. A clutch sleeve 105 is feathered on the shaft 93 and having suitable clutch jaws thereon engageable with corresponding jaws on the forward end of the sleeve 97 is provided to drive the shaft 93 from the sleeve 97 and spur gear 94. It

may thus be seen that the shaft 93 is rotated by means of the spur gear 94, clutch member 95, balls 96, sleeve 97, and clutch sleeve 105, and that upon overload of the shaft 93, the sleeve 97 will tend to remain stationary while the clutch member 95 will rotate, thus forming an automatic safety device to prevent overload of the motor and gears upon overload of the loading mechanism.

10 The material gathering mechanism comprises a plurality of scoops or blades 109 actuated by drive chains 110, 110 and 111, 111 having connection with said scoops at opposite sides thereof. The drive chains 110 are located adjacent the inner sides of the drive chains 88 in the side frame members 62. Each drive chain 110 is threaded under and around idler sprockets 112 and 113 near the lower rearward portion of the gathering element 2, an idler sprocket 114 near the lower forward portion of the gathering element 2, under idler sprockets 115 and 116 and over a driving sprocket 118, which sprocket is driven from the drive chain 88 by means of a stub shaft 119 and driven sprocket 120. See Figures 3 and 7.

15 The drive chains 111 are located adjacent the inner sides of the drive chains 110 in the side frame members 62 and each drive chain 111 is threaded around a drive sprocket 121 near the forward lower portion of the gathering element 2, over an idler sprocket 122 near the top portion of said gathering element and around a guide shoe 123 near the lower rearward portion of said gathering element.

20 The driving sprockets 121 are keyed on opposite ends of a drive shaft 124 and are driven from said shaft by means of driven sprockets 125 on said shaft. Drive chains 126 are threaded over the driven sprockets 125 and are driven from a transverse drive shaft 127 by means of driving sprockets 128. The drive shaft 127 is in turn driven from the 25 driving chains 88 by means of driven sprockets 130, 130 on opposite ends thereof.

25 Each scoop 109 has a forward digging edge 131 and is provided with upturned sides 132. Pins 133 extend outwardly from opposite sides of the rearward ends of the upturned sides 132 of each scoop 109. Each pin 133 is journaled in a depending portion 134 of a chain link 135 of the chain 111 and projects outwardly beyond said link. A rearwardly extending arm 136 fits on the outer end of each pin 133 and is held thereto by means of a pin 137. The arm 136 extends in a plane parallel to the plane of the scoop 109 and has a slot 138 extending longitudinally thereof for a portion of its length, which slot is engaged by a pin 140 fixed to the inner side of a link 141 of the drive chain 110. See Figures 8 and 9.

30 It should here be noted that the scoops 109 are pivotally supported at opposite ends on

the drive chains 111 and are thus moved around the orbital path of the drive chains 111 as said chains are driven by the chains 88. The scoops 109 also have slid able connection with the drive chains 110 at opposite ends thereof, which slid able point of connection is rearwardly of the point of connection of the scoop to the drive chains 111. Thus the scoops 109 are supported on the drive chains 111 and 110 and are guided by the 75 drive chains 110 as they are moved about the path of the drive chain 111. The relative speeds of the drive chains 110 and 111 may be varied but said chains are preferably driven at the same rate of speed. The path 80 of the drive chain 110 is so arranged with respect to the path of the drive chain 111 as to move the scoops 109 into the loose material in a substantially horizontal plane and pivot them upwardly, raise them and move 85 them rearwardly and upwardly along the gathering element 2 to discharge the material into the hopper 59 and conveyor 37. The scoops 109 are then moved downwardly and pivoted forwardly in a position to again enter 90 the loose material. It may thus be seen that the action of each scoop 109 is similar to that of a hand operated shovel, which action produces an efficient means for loading and causes a minimum amount of breakage of material. 95

35 A pan 142 is supported on the girder 71 in a usual manner and extends between the drive chains 111 and follows the contour of said chains from the lower forward portion of the gathering element 2 to the upper rearward portion thereof. The contour of this pan may be clearly seen in Figure 6 and it should be noted that the distance from the transverse plate 69 to the forward end of the pan 142 is such as to allow the scoop 109 105 to pass therethrough and prevent loss of loose material as said scoop is raised and that the rearward portion of said pan is so arranged with respect to the deflecting pan 60 110 as to prevent loss of loose material as it is 110 expelled from said scoop to the deflecting pan 60 and hopper 59.

40 It may thus be seen that a new and improved loading machine has been provided which comprises a gathering element and a storage and conveying element and is a mobile unit readily movable about a mine. The gathering element is provided with a plurality of continuously movable scoops movable longitudinally forward into the loose material in a substantially horizontal plane, and pivoted vertically and moved rearwardly and upwardly to raise the loose material and discharge it into a hopper and conveyor. The scoops are then moved vertically downwardly and pivoted forwardly to again enter the loose material adjacent the mine bottom and substantially parallel thereto. The gathering element may be moved into the loose material on the continuous tread devices 4 and 130

- may slide freely on the mine bottom and be adjusted to uneven mine bottoms or raised above the mine bottom for travelling about the mine, while the conveyor frame 17 may be vertically and horizontally adjusted to 5 accommodate various heights of mine cars and varying roof conditions and load material into said mine cars when the gathering element is at varying angular positions with respect to the mine car.
- 10 While I have herein shown and described one embodiment of my invention, it will be understood that the construction and arrangement of the various parts may be altered or changed without departing from 15 the spirit and scope thereof, and that I do not wish to be understood as limiting myself to the precise form illustrated, excepting as it may be limited in the appended claims.
- I claim as my invention:
- 20 1. In a loading machine, a base frame, and a gathering element supported thereon including a frame member pivotally supported on said base frame and extending forwardly therefrom and having a transversely 25 extending bottom surface adapted to slidably engage the ground and a plurality of continuously movable scoops extensible longitudinally forwardly of said base frame beyond the forward end thereof to penetrate 30 a pile of loose material along the ground and then pivotally movable upwardly and rearwardly to move said material into a conveyor.
2. In a loading machine, a base frame, and 35 a gathering element extending forwardly therefrom including a frame member pivotally supported on said base frame and extending forwardly therefrom and having a transversely extending bottom surface adapted to slidably engage the ground and a plurality of continuously 40 movable scoops supported by said frame member for movement in a vertical orbital path to engage a pile of loose material along the ground forwardly of said base frame and raise and convey said 45 loose material into a conveyor.
3. In a loading machine, a base frame, a gathering element including a forwardly extending frame member pivotally mounted 50 on said base frame to move about a horizontal transverse axis and having a transversely extending bottom surface adapted to slidably engage the ground during the loading operation, and gathering mechanism carried by 55 said gathering element comprising a plurality of scoops successively movable forwardly along the ground beyond said base frame to longitudinally penetrate a pile of loose material adjacent the ground, and then pivotally upwardly and rearwardly to raise said loose material and 60 discharge it into a conveyor.
4. In a loading machine, a base frame, a gathering element including a forwardly extending frame member pivotally mounted on 65
- said base frame to move about a horizontal transverse axis and having a transversely extending bottom surface adapted to slidably engage the ground during the loading operation, and gathering mechanism carried by 70 said gathering element comprising a plurality of scoops movable in a vertical orbital path to penetrate longitudinally a pile of loose material adjacent and parallel to the ground beyond said base frame and elevate and discharge said loose material into a conveyor. 75
5. In a loading machine, a base frame, a gathering element including a forwardly extending frame member pivotally mounted on said base frame to move about a horizontal transverse axis and having a transversely extending bottom surface adapted to slidably engage the ground during the loading operation, and gathering mechanism carried by 80 said gathering element comprising a scoop supported on orbitally movable drive chains at opposite ends thereof, and movable forwardly along the ground beyond said base frame to penetrate a pile of loose material adjacent the ground and then pivotally upwardly and rearwardly to raise said loose material and discharge it into a conveyor. 85
6. In a loading machine, a base frame, a gathering element including a forwardly extending frame member pivotally mounted on said base frame to move about a horizontal transverse axis and having a transversely extending bottom surface adapted to slidably engage the ground during the loading operation, and gathering mechanism carried by 90 said gathering element comprising a scoop supported on orbitally movable drive chains at opposite ends thereof, and movable forwardly along the ground beyond said base frame to penetrate a pile of loose material adjacent the ground and then pivotally upwardly and rearwardly to raise said loose material and discharge it into a conveyor. 95
7. In a loading machine, a base frame, a gathering element pivotally mounted thereon to move about a horizontal transverse axis and extending forwardly therefrom, and gathering mechanism carried by said gathering element comprising a scoop having pivotal connection with a vertically disposed orbitally movable non-circular drive member, and having slidable connection with another vertically disposed orbitally movable non-circular drive member for moving said scoop forwardly along the ground to penetrate a pile of loose material adjacent the mine ground and then pivotally upwardly and rearwardly to raise said loose material and discharge it into a conveyor. 110
8. In a loading machine, a base frame, a gathering element pivotally mounted thereon to move about a horizontal transverse axis and extending forwardly therefrom, and gathering mechanism carried by said gathering 115
- 120
- 125

- ing element comprising a scoop having pivotal connection at opposite ends thereof with vertically disposed orbitally movable non-circular drive members, and having slidable connection with other vertically disposed orbitally movable non-circular drive members at opposite ends thereof, said drive members each being driven at relative speeds with respect to each other to move said scoop forwardly along the ground to penetrate a pile of loose material adjacent the ground and then pivotally upwardly and rearwardly to elevate said loose material and discharge it into a conveyor.
9. In a loading machine, a base frame, a gathering element pivotally mounted thereon to move about a horizontal transverse axis and extending forwardly therefrom, and gathering mechanism carried by said gathering element comprising a plurality of scoops having pivotal connection at opposite ends thereof with vertically disposed orbitally movable non-circular flexible drive members, and having slidable connection with other vertically disposed orbitally movable non-circular flexible drive members at opposite ends thereof, said drive members each being driven at relative speeds with respect to each other to move said scoops successively forwardly along the ground to penetrate a pile of loose material adjacent the ground and then pivotally upwardly and rearwardly to elevate said loose material and discharge it onto a conveyor.
10. In a loading machine, a base frame, a gathering element pivotally mounted thereon to move about a horizontal transverse axis and extending forwardly therefrom, and gathering mechanism carried by said gathering element comprising a plurality of scoops having pivotal connection at opposite ends thereof with vertically disposed orbitally movable non-circular drive chains and having slidable connection with other vertically disposed orbitally movable non-circular drive chains at opposite ends thereof, said second mentioned drive chains being movable in another vertical orbital non-circular path and said drive chains each being driven at relative speeds with respect to each other to move said scoops successively forwardly along the ground to penetrate a pile of loose material adjacent the ground and then pivotally upwardly to elevate said loose material and discharge it onto a conveyor.
11. In a loading machine, a base frame, a gathering element pivotally mounted thereon to move about a horizontal transverse axis and extending forwardly therefrom, and gathering mechanism carried by said gathering element comprising a scoop having pivotal connection at opposite ends thereof with drive chains movable in a vertically disposed non-circular orbital path, and having slidable connection with other drive chains movable in a different vertically disposed non-

circular orbital path, said slidable connection with said second mentioned drive chain being rearwardly of said scoop and said point of pivotal connection with said first mentioned chain.

12. In a loading machine, a base frame, a gathering element pivotally mounted thereon to move about a horizontal transverse axis and extending forwardly therefrom, and gathering mechanism carried by said gathering element comprising a scoop having pivotal connection at opposite ends thereof with drive chains movable in a vertically disposed non-circular orbital path, and having slidable connection with other drive chains movable in a different vertically disposed non-circular orbital path, said slidable connection with said second mentioned drive chain being rearwardly of said scoop and said point of pivotal connection with said first mentioned chain, and means for driving said chains at relative speeds with respect to each other to move said scoops successively forwardly along the ground to penetrate a pile of loose material adjacent the ground and then pivotally upwardly and rearwardly to elevate said loose material and discharge it onto a conveyor.

13. In a loading machine, a base frame, a conveyor thereon and pivotally movable with respect thereto about a vertical axis, a gathering element pivotally mounted on said base frame forwardly of said conveyor to move about a horizontal transverse axis so as to be moved into and out of engagement with the ground and having a transversely extending bottom surface adapted to slidably engage the ground during the loading operation, and gathering mechanism carried by said gathering element comprising a plurality of scoops successively movable forwardly along the ground beyond said base frame in a plane parallel to the ground to penetrate a pile of loose material adjacent the ground and then pivotally upwardly and rearwardly to elevate said loose material and discharge it onto said conveyor.

14. In a loading machine, a base frame supported on a pair of laterally spaced continuous tread devices, a motor, a conveyor supported on said base frame for pivotal movement with respect thereto about a vertical axis, means connectible with said motor for moving said conveyor about its axis of pivotal connection to said base frame, a gathering element pivotally mounted on said base frame forwardly of said conveyor to move about a horizontal transverse axis so as to be moved into and out of engagement with the ground and having a transversely extending bottom surface adapted to slidably engage the ground during the loading operation, means connectible with said motor for moving said gathering element into and out of engagement with the ground, gathering

mechanism carried by said gathering element comprising a plurality of scoops, and means for driving said scoops from said motor for successively moving said scoops forwardly 5 along the ground beyond said base frame in a plane parallel to the ground to penetrate a pile of loose material adjacent the ground, and then upwardly and rearwardly to elevate said loose material and discharge it onto said conveyor.

15. In a loading machine, a base frame supported on a pair of laterally spaced continuous tread devices, a motor, a conveyor supported on said base frame for pivotal movement with respect thereto about a vertical axis, means connectible with said motor for moving said conveyor about its axis of pivotal connection to said base frame, a gathering element pivotally mounted on said 20 base frame forwardly of said conveyor to move about a horizontal transverse axis so as to be moved into and out of engagement with the ground and adapted to slidably engage the ground during the loading operation,

25 means connectible with said motor for moving said gathering element into and out of engagement with the ground, gathering mechanism carried by said gathering element comprising a plurality of scoops, and means 30 for driving said scoops from said motor for successively moving said scoops forwardly along the ground in a plane parallel to the ground to penetrate a pile of loose material adjacent the ground, and then upwardly and 35 rearwardly to elevate said loose material and discharge it onto said conveyor comprising a plurality of drive chains connected to each of said scoops and movable in different vertically disposed non-circular orbital paths.

40 16. In a coal loading machine, a base frame, a motor, a gathering element forwardly of said motor and movable into and out of engagement with a mine bottom, gathering mechanism carried by said gathering element 45 comprising a plurality of scoops movable in a vertically disposed non-circular orbital path, and means for driving said scoops from said motor in said vertically disposed non-circular orbital path comprising a plurality of drive members connectible with said 50 scoops and movable in different vertically disposed non-circular orbital paths.

55 17. In a coal loading machine a base frame, a motor, a gathering element forwardly of said motor and movable into and out of engagement with a mine bottom, gathering mechanism carried by said gathering element comprising a plurality of scoops movable 60 in a vertically disposed non-circular orbital path, and means for driving said scoops from said motor in said vertically disposed non-circular orbital path comprising a plurality of flexible drive members connectible with 65 opposite sides of said scoops and movable in

a plurality of vertically disposed non-circular orbital paths.

18. In a coal loading machine, a base frame, a motor, a gathering element forwardly of said motor and movable into and out of engagement with a mine bottom, gathering mechanism carried by said gathering element comprising a plurality of scoops movable in a vertically disposed non-circular orbital path, and means for driving said 75 scoops from said motor in said vertically disposed non-circular orbital path comprising flexible drive members connectible with opposite sides of each of said scoops near the rearward end thereof and movable in a vertically disposed non-circular orbital path, and other flexible drive members connectible with opposite sides of each of said scoops rearwardly of the point of connection of each of said scoops to said first mentioned flexible 80 drive members and movable in a different vertically disposed non-circular orbital path than said first mentioned flexible drive members.

19. In a coal loading machine, a base frame, a motor, a gathering element forwardly of said motor and movable into and out of engagement with a mine bottom, gathering mechanism carried by said gathering element comprising a plurality of scoops 90 movable in a vertically disposed non-circular orbital path, and means for driving said scoops from said motor in said vertically disposed non-circular orbital path comprising drive chains pivotally connectible with opposite sides of each of said scoops near the rearward end thereof and movable in a vertically disposed non-circular orbital path, and other drive chains having sliding connection with opposite sides of each of said 95 scoops rearwardly of the point of connection of each of said scoops to said first mentioned drive members, said last mentioned drive chains being movable in different vertically disposed non-circular orbital paths than said 100 first mentioned drive chains, all of said chains successively moving said scoops forwardly along the ground in a plane substantially parallel with the ground to penetrate a pile of loose material adjacent the ground, and then 105 pivotally upwardly and rearwardly to elevate said loose material and discharge it onto a conveyor.

20. In a coal loading machine, a base frame, a motor, a gathering element forwardly of said motor and movable into and out of engagement with a mine bottom, gathering mechanism carried by said gathering element comprising a plurality of scoops movable 110 in a vertically disposed non-circular orbital path, and means for driving said scoops from said motor in said vertically disposed non-circular orbital path comprising a drive chain pivotally connectible with each side of each of said scoops near the rearward end 115 120 125 130

thereof and movable in a vertically disposed non-circular orbital path, and a guiding chain having slideable connection with each side of each of said scoops rearwardly of the point of connection of each of said scoops to said first mentioned drive members, said guiding chains being movable in different vertically disposed non-circular orbital paths than said driving chains, and means for driving said driving chains and said guiding chains simultaneously at relative speeds with respect to each other for successively moving said scoops forwardly along the ground in a plane substantially parallel with the ground to penetrate a pile of loose material adjacent the ground and then pivotally upwardly and rearwardly to elevate said loose material and discharge it onto a conveyor.

Signed at Chicago, in the county of Cook and State of Illinois.
